UNITED STATES PATENT OFFICE.

WILLIAM H. I. WELCH, OF BOW, ENGLAND, ASSIGNOR TO THE LAMP MANUFACTURING COMPANY, LIMITED, OF LONDON, ENGLAND.

OVERHEAD REGENERATIVE GAS-LAMP.

SPECIFICATION forming part of Letters Patent No. 682,896, dated September 17, 1901.

Application filed April 5, 1901. Serial No. 54,505. (No model.)

To all whom it may concern:

Be it known that I, WILLIAM HENRY ISAAC WELCH, a citizen of England, residing at 68 Coborne road, Bow, in the county of London, 5 England, have invented a certain new and useful Improvement in Overhead Regenerative Gas-Lamps, (for which I have obtained a patent in Belgium, dated September 19, 1900, No. 152,135; in France, dated September 18, 1900, No. 303,864, and in Great Britain, dated September 18, 1900, No. 16,626,) of which the following is a specification.

This invention relates to overhead gas-lamps in which the flame is supplied with air heated by passing through channels the walls of which are heated by the passage of the hot products of combustion from the flame.

I shall describe my invention, referring to the accompanying drawings, which show a 20 lamp suited for fixing to the ceiling of a railway-carriage compartment.

Figure 1 is a vertical section of a lamp according to my invention, the external chimney and wind-guards, which form no part of 25 my invention, being shown in outline. Fig. 2 is a plan on the line 2 2 of Fig. 1.

The main inlets *c* for the air to supply the flame and the central outlet *b* for the products of combustion to the chimney *n* are 30 formed in a casting *a*, which, as well as the flange *f* of the glass *g*, is carried on a lip in-

wardly projecting from a flanged ring *l*, which is fixed to the ceiling of the compartment. Under the central outlet *b* a conoidal shell *d* is fixed to *b*, and below it a reflecting-plate *r* 35 is attached by several screws *p* to the casting *a*. The air that enters by the circular openings *c*, heated by passing in contact with the hot wall of *b* and over the heated shell *d*, passes by holes *e* through the plate *r*, and additional air enters the globe through holes *h* 40 to supply the flat flame *s*.

Having thus described the nature of this invention and the best means I know of carrying the same into practical effect, I claim— 45

An overhead regenerative gas-lamp having a circular casting over the burner with a central outlet to the chimney, said casting containing a series of down-draft-holes surrounding this central outlet, and also having air-admission holes near its periphery, and a reflecting-plate of annular form secured to the casting and provided with a central opening above the burner; substantially as described. 50

In testimony whereof I have hereunto set 55 my hand in presence of two subscribing witnesses.

W. H. I. WELCH.

Witnesses:

GERALD L. SMITH,
EDWARD GARDNER.
